BATHING SUIT

Virginia Bowman, New York, N. Y.

Application January 28, 1939, Serial No. 253,367

2 Claims.

(Cl. 2—67)

This invention relates generally to garments for men or women and more particularly to swimming or bathing suits.

A bathing suit including a pair of relatively short trunks or pants forming a nether garment together with a top piece or body garment which is a separate unit, and which when worn, overlies or overhangs the trunk or nether garment, has long been known in the bathing suit art. Later the upper edge of the nether garment was integrated with the inner surface of the waist portion of the body garment to form a one-piece bathing suit having a skirt overlying the nether garment. Since the material comprising the upper portion of the nether garment was unseen, it merely added extra weight and cost to the entire garment.

For the purpose of securing a skirt effect, I have previously made bathing suits in which the nether garment was extremely reduced in height so that the upper edge of the nether garment was integrated with the inner surface of the body garment very close to the lower edge of said body garment. While this resulted in a considerable saving of material and in the weight of the entire garment, the same was unsatisfactory in that while it aimed to give a skirt effect, what resulted was the effect of a narrow ruffle on a one-piece bathing suit. I have also previously made bathing suits which were of the so-called "one-piece" construction in which the entire garment was longer than a normal "one-piece" suit of the same size by an amount twice the length of the skirt which it was desired would appear in the finished product. This skirt was formed by making a horizontally extending circumferential pleat. This last mentioned construction was equally unsatisfactory in that the finished garment appeared to be only a "one-piece" suit with a narrow ruffle, the desired skirt effect being entirely lost. These garments have been improved by the present invention so that a true skirt effect is attained.

Among the objects of the present invention is the provision of a novel bathing suit structure which with a minimum of weight and material, produces a true skirt effect.

Another object herein is the provision of bathing suit structure essentially of the "one-piece" type and in which a proper and highly desirable fit is provided and in which proper fullness for comfort is obtained without losing the desirable slenderizing effects of a rather snugly fitted garment.

Another object herein is the provision of a bath-

ing suit structure in which considerable economies are accomplished by reason of the reduction in the total amount of material used and by reason of a reduction in the number of operations. Furthermore, these operations are of such a nature that they are more easily performed.

A further object herein is a provision of bathing suit structure in which the desired objects may be accomplished in all types of bathing suit construction, as for example, suits manufactured of smooth surfaced "Lastex" fabrics, Matelasse, or of woven or knitted fabrics having the necessary elastic qualities. The present improved construction is readily adapted to suits which are either fully lined, partially lined or unlined. The present construction is also readily adapted for use with suits made of sheet rubber with either cemented or stitched seams.

These objects and further ends and advantages will more fully appear in the progress of this disclosure and as pointed out in the appended claims. In the drawings forming a material part of this disclosure, similar reference characters designate corresponding parts throughout the several views and in which:

Fig. 1 is a front view in perspective showing a first embodiment of the invention as worn.

Fig. 2 is a rear view in perspective of the embodiment shown in Fig. 1.

Fig. 3 is a side view in perspective of the first embodiment as seen from the wearer's left.

Fig. 4 is a schematic or diagrammatic sectional view as seen from the plane 4—4 on Fig. 3.

Fig. 5 is a fragmentary central vertical sectional view as seen from the plane 5 on Fig. 2.

Fig. 6 is an enlarged sectional view as seen from the plane 6—6 on Fig. 3.

Fig. 7 is a developed plan view showing the two rear panels of the first embodiment.

Fig. 8 is a developed plan view showing the front panel of the first embodiment.

Fig. 9 is a developed plan view of the crotch gusset of the first embodiment.

Fig. 10 is a developed plan view of the front crotch element of the first embodiment.

Fig. 11 is a fragmentary view taken similarly to Fig. 1 and in which the lower portion of the front panel has been pulled away to further expose the parts for the purpose of clarity.

Fig. 12 is a front view in perspective showing a second embodiment of the invention as worn.

Fig. 13 is a fragmentary central vertical sectional view taken similarly to Fig. 5 but showing instead the second embodiment of the invention.

Fig. 14 is a fragmentary view taken similarly

to Fig. 12 and in which the lower portion of the front panel has been pulled away to more clearly display the parts and the integration thereof.

Fig. 15 is a developed plan view of the front panel of the second embodiment.

Fig. 16 is a developed plan view of the front pantie or trunk of the second embodiment.

Fig. 17 is a front view in perspective showing a third embodiment of the invention as worn.

Fig. 18 is a developed plan view of the front panel and pantie or trunk of the third embodiment.

Fig. 19 is a developed plan view of the pocket insert as utilized in the third embodiment.

Fig. 20 is a developed plan view showing the two rear and side panels of the third embodiment.

Right and left hand designations herein are intended as corresponding to the right and left hands of a wearer in the garment.

Turning now to the first embodiment of the invention illustrated in Figs. 1 to 11 inclusive, the bathing suit generally indicated by numeral 30 comprises a front panel 31, having bust pockets 32 and 33, shoulder straps 35 and 36, back panels 37 and 38, back ties 39 and 40 and a crotch gusset 41.

Since the construction of the suit 30 above the waist 29 may be of any desired construction, that shown is merely by way of example and will not be described in further detail. It will be obvious to those skilled in the art to which the present invention pertains that different types of construction may be used with the novel nether or lower portion of the garment herein disclosed.

The lower portion 34 of the front panel has a hem portion 42 which extends from the left hand side edge 43 to the right hand side edge 44 and from the dash-double-dot fold or hem line 45 (Fig. 8) to the lower horizontal edge 46 of the front panel. The lower horizontal edge 46 of the front panel 31 at the center thereof is provided with a semi-circular or arc shaped pocket forming extension or tab 47 having a substantially convex edge 55. While the extension 47 is shown as integral with the lower portion 34, it may of course be a separate piece attached to the lower portion 34 since such attachment is not normally visible in the finished garment as worn. The front crotch element 48 (see Fig. 10) at the lower edge thereof is provided with an inverted V-shaped notch 49, and the lower edge includes two downwardly converging edges 50 and 51. The upper horizontally disposed edge 52, at the center thereof is provided with a semi-circular or arc shaped pocket forming extension or tab 53 having a substantially convex edge 54.

The two rear panels 37 and 38 are shaped in accordance with standard tailoring practice in the bathing suit art and they include upper back-line edges 56 and 57, left hand side edge 58 and right hand side edge 59, lower rear crotch portions 60 and 61, gusset conforming inverted V-indentations 62 and 63, and rear central edges 64 and 65.

The crotch gusset 41 includes rear crotch portion engaging edges 66 and 67, inner crotch forming edges 68 and 69 and a front crotch engaging edge 70.

In order that the arrangement and integration of the parts may be fully understood, one method of assembly which it has been found requires a minimum of stitching operations will now be

set forth. (A) The previously formed bust pockets 32 and 33 are stitched together preferably by a so-called "Merrow" sewing machine stitch. (B) The brassière portion composed of the previously integrated bust pockets is Merrow stitched to the upper edges of the front panel 31, along the lines 71 and 72. (C) The upper horizontal edge 52 and the convex edge 54 of the front crotch element 48 is stitched to the lower horizontal edge 46 and the convex edge 55 of the front panel 31 by a single row of Merrow stitches. (D) The front crotch engaging edge 70 is Merrow stitched to the edges of the V-shaped notch 49 in the lower portion of the front crotch element 48. (E) The rear central edges 64 and 65 are Merrow stitched together. (F) The inverted V-indentations 62 and 63 are Merrow stitched to the rear crotch portion engaging edges 66 and 67 respectively. (G) The lower portion of the front panel is folded inwardly or rearwardly as viewed in Fig. 8, along the fold or hem line 45 through one hundred and eighty degrees. This folding operation places the crotch pocket generally indicated by numeral 73, upwardly and rearwardly of the front panel lower portion 34 (see Fig. 5). (H) Two vertical side seams formed by Merrow stitching are next made joining the front 31 (as already completed) to the back generally indicated by numeral 74. These seams in effect join the edges 43 and 44 to the edges 58 and 59 respectively. (I) All of the previously Merrow stitched seams are next "cover" stitched for the purpose of preventing splitting. (J) Finally, a single row of cover stitches 84 is put into the garment along a path indicated by the arrows in Fig. 4. Previous to this last mentioned stitching operation, the lower raw edges of the lower rear crotch portions 60 and 61, the inner crotch forming edges 68 and 69 and the downwardly converging edges 50 and 51 have been turned inwardly in order to form a hem. The stitches 84 formed and indicated by the arrows 75 and 76 serve to hem the crotch portion of the suit 30 while the stitches 78 indicated by the arrows 77 are made along the lower portion 34 of the front panel 31 along the dash-triple-dot lines 79 (Fig. 8) serving to maintain the hem produced by the fold along the line 45. The row of stitches 78 is positioned so as not to engage the edges 46 and 52 which have been previously connected by the row of Merrow stitches set forth in operation C above. The row of stitches 78, does not anywhere, engage the crotch pocket 73.

When the bathing suit 30 is worn, owing to the elasticity of the fabric of which it is made, the same conforms in all respects, except one, to the contour of the body. The one portion of the suit which does not conform to the contour of the body is the front skirt generally indicated by numeral 80. This is so because the inverted crotch pocket 73 allows an excess of material so that the front skirt 80 is only loosely connected to the bathing suit 30 at the outer side edges thereof. This construction and position of the skirt 80 is clearly indicated in Figs. 4, 5 and 6. In Fig. 6, it may be seen that while the crotch gusset 41 and the lower portion (exclusive of the extension 53) of the front crotch element 48 engage the body surface, the extension 53 together with the extension 47 permit the skirt 80 to hang loosely and spaced from the body. The tendency of the skirt 80 to hang forwardly and away from the body contour between the uppermost portions of the thighs is further

caused by the tension existing across the skirt 80 by reason of the attachment of its outer edges at the lowest portions of the side seams, at 83, 183.

As indicated by the dash-dot line 81 in Fig. 3, it may be seen that the base of the trunk of the body curves inwardly a substantial amount and if the central portion of the skirt 80 were attached to the front of the crotch portion from one side of the bathing suit to the other, the skirt would be forced to follow the contour of the crotch portion at that point and would go in between the legs as indicated by the dotted lines 82 in Fig. 4 and the dot-dash lines 83 in Fig. 5. The skirt then caused to take a concave configuration along its plane, buckles and ruffles, and will project outwardly at an angle from the vertical as indicated in Fig. 5. This effect is very undesirable from both practical and aesthetic standpoints and entirely defeats the purpose of having a front skirt on a suit altogether. By means of applicant's improved construction, the skirt 80 is only loosely connected to the body of the garment along a predetermined area, that is to say, the upper portion of the front crotch, and is thereby permitted to hang straight and in a planar condition vertically disposed with relation to the adjacent suit portions. As may be seen in Figs. 8 and 10, the only additional material required to secure this desirable effect is in the extensions 47 and 53.

Another saving of material in the present construction is provided for in the utilization of the converging edges 50 and 51 which "hem to nothing" in meeting the upper edge 52. Since the folded portion of the hem at the lower edge of the lower front portion 34, that is to say, the fold of material formed between the fold line 45 and the row of stitches 78 or the line 79 serves as a pantie gusset to cover the space indicated at numeral 82 on Fig. 11. The upper edge 52 of the front crotch element 48 thus is supported from above by its attachment to the edge 46 and is not directly supported at the side edges. This construction while assuring adequate coverage of the body, and no apparent difference of appearance of the suit as normally worn, permits a much simpler sewing operation in connecting the edges 43 and 58, and 44 and 59 respectively since when the front crotch element extends to the side seams, considerable bulkiness occurs which not only impairs the appearance of the garment at the points 83 and 183 but also makes the sewing operation through so many thicknesses of cloth difficult and time-consuming.

Turning now to the second embodiment of the invention illustrated in Figs. 12 to 16 inclusive, the bathing suit indicated generally by numeral 30' is generally of similar construction to the one described as the first embodiment.

The principal differences occur in the utilization of a separate lining generally indicated by numeral 90, and in a change in the configuration of the pantie pocket forming extensions 47' and 53'.

Since back panels 37 and 38 and a crotch gusset 41 may be used without any change in connection with the second embodiment, these parts have not been specifically illustrated nor will the description thereof be repeated. The various lining pieces are substantially of the same configuration as the panel or gusset piece with which they are adapted to be connected. As shown in Figs. 13 and 14, the front lining

panel 91 is attached at its edges to the upper edges 11' and 12' and on its sides to the edges 43' and 44' of the front panel 31' and 34' while the lowermost edge of the lining 91 is attached to the converging lower edges 50' and 51' of the front pantie or trunk 48'. The full length of the lining 91 is such that it is adapted to lie smooth on the inner surface of the front panel 31' and the front pantie 48' after the convex edges 54' and 55' have been connected together and the lower portion 34' of the front panel has been folded inwardly and upwardly, or rearwardly, through one hundred and eighty degrees along the dash-double-dot lines 45'. The upper edge of the pantie pocket 73', that is to say the two abutting edges 55' and 54' are stitched to the outer surface of the lining 91 by means of a row of stitches 92. This connection of the upper edge of the pocket 73' to the lining 91 by means of stitches 92 gives further support to the forward upper front edge of the pantie 48' and is desirable where the bathing suit 30' is of a lined construction. Note, however, that the lining is not connected adjacent the stitches 92 to the front panel lower portion 34' so that any downward pull on the stitches 92, that is to say, on the upper edge of the pantie pocket 73' is taken up by the vertical elasticity of the lining 92 which does not affect the normal planar vertical condition of the skirt 80' between the upper portion of the legs.

The lining portion 93 which lines the crotch gusset 41 may be, if desired, of water-proof material while the lining portion 99 which lines the rear panels of the suit 30' is seen in Fig. 13.

As seen in Fig. 16, the vertically disposed outwardly diverging side edges 94 and 95 extend sufficiently in a vertical direction so that they may be engaged by the stitches which connect the front and rear halves of the garment. This construction is seen in the lower portion of Fig. 14 and may be contrasted with the structure disclosed in Fig. 11.

As will be obvious to those skilled in the art, the configuration of the lower edge of the front pantie 48' may be interchanged with the configuration of the front pantie 48. The configuration of the lower edge of pantie 48 saves material and avoids bulkiness at the base of the garment side seams.

Turning now to the third embodiment of the invention illustrated in Figures 17 to 20 inclusive, the bathing suit generally indicated by numeral 30'' is of a one-quarter skirt construction. The front panel 31'' is much narrower in width than the other embodiments and the lower portion 34'' of the front panel is integral with the front pantie portion 48''.

The back panels 31'' and 38'' are cut sufficiently wide so that the side edges 58'' and 59'' are joined to the edges 43'' and 44'' along lines substantially on the front of the garment 30''.

The lower portion 34'' of the front panel where it joins the pantie portion 48'' is provided with a horizontally directed slit forming edges 46'' and 52'' into which is suitably stitched the gusset 41'' which when folded inwardly along the dash-triple-dot lines 100 forms a pantie pocket 73''.

The V-shaped notch of the pantie portion 48'' is connected to a crotch gusset like gusset 41 which is in turn connected to the lower edges of the rear inverted V indentations 62'' and 63''.

Before the front and back panels of the suit 30'' are connected along the seams 101 and 102,

the lower portion 34" of the front panel 31" is folded inwardly about the dash-double-dot line 45", which moves the pantie pocket into the position shown in Fig. 17.

The construction of the third embodiment presents several advantages. In the first place, side seams as commonly known in the bathing suit art are eliminated so that a smooth side line in the garment is obtained. Separate bust pockets are unnecessary as the rear panel upper portions and the front panel upper portion provide adequate fullness at these points. The actual additional fabric required to form the smooth hanging skirt 80" is obtained from only the gusset 47" and the lower front pantie portion 48" which lies below the edge 52.

In each of the embodiments described, the novel pantie pockets 13, 13', and 13" with only a small amount of material provide adequate and outwardly invisible fullness so that the skirts 80, 80', and 80" hang straight and smooth and give the true effect of a "two-piece" bathing suit although the suits 30, 30', and 30" require only slightly more material and labor than real "one-piece" construction.

The foregoing description has been made rather detailed for clearness of understanding only, and no unnecessary limitations should be understood therefrom, but the appended claims should be construed as broadly as permissible in view of the prior art.

I claim:

1. A bathing suit comprising: a rear panel the upper portion of which forms the back of the suit, and the lower portion of which forms the rear part of the crotch of the suit; a front

panel the upper portion of which forms the front of the suit and the lower portion of which covers the lower front portion of the human figure when worn; said front panel having an inturned lower

5. edge folded upon itself and secured thereto in an upwardly folded position, the upper portion of said edge terminating in a downwardly extending first convex tab; a front crotch element connected at the lower central portion thereof to the lower central portion of said rear panel, said crotch element having an upper edge including a second convex tab, said first and second tabs being interconnected at the edges thereof forming a pantie gusset positioned rearwardly of the 15 lower portion of the front panel.

2. A bathing suit comprising: a rear panel the upper portion of which forms the back of the suit, and the lower portion of which forms the rear part of the crotch of the suit; a front panel the upper portion of which forms the front of the suit and lower portion of which covers the lower front portion of the human figure when worn; said front panel having an inturned lower edge folded upon itself and secured thereto in 20 an upwardly folded position, the upper portion of said edge terminating in a downwardly extending first convex tab, a front crotch element connected at the lower central portion thereof to the lower portion of the said rear panel, said 25 crotch element including a central convex tab and lateral tabs, said first and second convex tabs being interconnected along their convex edges; the lateral tabs of the crotch element being connected to said lower edge at the sides of the first convex tab.

VIRGINIA BOWMAN.
